UNITED STATES PATENT OFFICE.

CARLOS J. BASSLER, OF PORTLAND, OREGON, ASSIGNOR TO AMERICAN LIQUID METER COMPANY, OF PORTLAND, OREGON, A CORPORATION OF WASHINGTON.

FLUID METER.

Application filed June 8, 1921. Serial No. 476,057.

To all whom it may concern:

Be it known that I, CARLOS J. BASSLER, a citizen of the United States of America, and resident of the city of Portland, in the county of Multnomah, State of Oregon, have invented certain new and useful Improvements in Fluid Meters, of which the following is a specification.

My invention relates to an improvement in fluid meters, it is particularly intended as an improvement upon the meter shown in my Patent No. 1,355,208, and is capable of all the uses and variations described in connection with this meter.

15 An important object of the present invention is to form a more perfect meter of the type shown in my patent above referred to, in that it has less tendency to cock or stick, and in that it operates more smoothly and 20 exactly, and is practically noiseless in operation.

Another object is to provide means for lessening the strain upon all parts of the meter, due to the rapid reversal and exact 25 positioning of parts requisite for exact measurement.

Another object is to provide a fluid meter employing only a single control valve at either end of the measuring cylinder.

30 My invention comprises those novel parts and combinations thereof which are shown in the accompanying drawings, described in the specification, and particularly defined by the claims terminating the same.

35 In the accompanying drawing, which shows an axial section through a meter, I have shown my invention in the form of construction which is now preferred by me.

As in general my present device resembles 40 that shown in my patent and in the application referred to above, it will not be necessary to explain its construction in great detail. The meter is of the positively-acting type, in which a piston 4 is reciprocable 45 within a cylinder 1. This cylinder is closed by the heads 10; in each of which are mounted the bushings or seats 12 for the tubular, axially-reciprocable inlet and outlet valves 2. Inlet passages 14 and outlet passages 15

50 in the cylinder and heads, communicate respectively with ports 16 and 17 in the bushings 12. The valve 2 preferably is provided with a single port 21, in its sides, which is adapted to communicate at the proper time 55 with the port 16 or 17, as the case may be.

The valves at opposite ends of the piston are rigidly connected by a rod 80, extending through the hub 40 of the piston, and suitably secured to the valve 2.

I desire to provide dashpots or similar yielding and cushioning devices to check the valves at the end of their outward stroke. In caps or plugs 19 secured in the ends of the cylinder and in effect forming part of the cylinder head 10, in position to receive the outer ends of the tubular valve 2, I therefore form annular grooves 18, of slightly greater width than the thickness of the valve walls. These grooves form dashpots for the valves, and eliminate pounding and wear thereupon. It is very desirable that stops be provided to accurately limit the movement of the valves, and to cause their ports to register exactly, but it is equally desirable that pounding should be eliminated. Other forms of cushioning devices may be employed for other types of valves, that described being most suitable for my preferred type of valve.

I employ a suitable power storage mechanism to actuate the valve, this being energized by the piston in its travel, and tripped when the piston has reached the predetermined limit of its travel in each direction, to thereby reverse the position of the valves and the motion of the piston. The particular form of power storage mechanism forms no part of this invention. It consists of the springs 41 surrounding the rod 80 at each side of the piston 4, which springs rest at one end upon the shoulders 42, secured upon the rod 80, or abutting against the inner ends of the valves. The outside of the member having thereon the shoulder 42 forms a shoulder 43, against which a cooperating shoulder 50 carried by a pivoted dog 5 normally lies to prevent outward movement of the spring 41 and shoulder 42 under pressure. Beveled surfaces 44 are provided near the hub of the piston 4, which engage the trips 53, which may be of any suitable or desired construction, to release the power storage mechanism and to reverse the valves. The detent or dog 5 is in all respects similar to that shown in my patent and application referred to above, and need not be described here in detail.

The cushioning device, or dashpot, retarding the final portion of the valve stroke, does not prevent rapid reversal of the parts,

but it eliminates the pounding, the noise, and the strain on all parts of the mechanism, while yet permitting accurate positioning of the valves. The single valve construction described is cheap to make and operates satisfactorily. All movements of the valves occur in an axial direction and upon the axis of the meter, hence cocking or sticking of the valves is reduced to a minimum. It is to be understood that mere reversals of the valve and bushing ports are essentially the same as the invention described, and are comprised in the claims following hereafter.

What I claim as my invention is:

- 15 1. In a fluid meter of the positively-acting type, mechanism which is reversible in action for controlling the inlet to and outlet from said meter, and means for cushioning said reversible mechanism at the ends of its stroke comprising a member having a recess of the shape of the adjoining end of the reversible mechanism, and slightly larger than this end.
- 20 2. In a fluid meter of the positively-acting type, mechanism which is reversible in action including tubular valves controlling the inlet to and outlet from said meter, said valves being axially reciprocable, and a cap covering the outer ends of each of said valves, and positively limiting the stroke thereof, said cap having an annular groove therein positioned to receive the end of its valve, and of slightly greater width than the thickness of the walls thereof.
- 25 3. In a fluid meter, in combination, a cylinder having inlet and outlet passages communicating with each end thereof, a piston reciprocable in said cylinder, two tubular combined inlet and outlet valves one in each end of the cylinder and each having a port in its side and being movable to control the respective passages in its respective end of the cylinder, and means at each end of the cylinder and operable by movement of the piston for limiting movement thereof in its 40 respective direction.
- 45 4. In a fluid meter, in combination, a cylinder having inlet and outlet passages communicating with each end thereof, a piston reciprocable in said cylinder, a pair of tubular combined inlet and outlet valves one in

each end of the cylinder and each having a single port in its side, said inlet and outlet passages being spaced axially of the valve, and the valve being reciprocable to register with either of said passages, and means at each end of the cylinder and operable by movement of the piston for limiting movement thereof in its respective direction.

5. In a fluid meter, in combination, a cylinder having inlet and outlet passages communicating with each end thereof, a piston reciprocable in said cylinder, a combined inlet and outlet valve in each end of the cylinder and each having a single port in its side, said inlet and outlet passages being spaced axially of the valve, and the valve being reciprocable to register with either of said passages, means at each end of the cylinder and operable by movement of the piston for limiting movement thereof in its respective direction, the axes of said valves extending in the same direction as the axis of the cylinder, and a rod passing through the piston and rigidly connecting said valves.

6. In a fluid meter, in combination, a cylinder having inlet and outlet passages communicating with ports in each end thereof, a piston reciprocable in said cylinder, two tubular inlet and outlet valves, said valves positioned at an opposite end of the cylinder, and each having a port in its sides and axially reciprocable to control the respective ports in its respective end of the cylinder, the cylinder head having therein a stop to limit the travel of each valve and having an annular groove positioned to receive the end of each valve and forming a dash-pot therefor, a rod penetrating the piston and connecting the valves at opposite ends of the cylinder, power storage means energized by the piston in its travel for tripping said valves, and a detent for said power storage mechanism at each end of the cylinder releasable by continued travel of said piston.

Signed at Portland, Multnomah County, Oregon, this 31st day of May, 1921.

CARLOS J. BASSLER.
